UNITED STATES PATENT OFFICE.

ALBERT MARSH AND HERBERT PHILIP ALAIS, OF LONDON, ENGLAND.

TICKET-DELIVERING MACHINE.

Application filed August 27, 1923. Serial No. 659,606.

To all whom it may concern:

Be it known that we, ALBERT MARSH and HERBERT PHILIP ALAIS, subjects of the King of Great Britain and Ireland, residing at 5 185, Lauderdale Mansions, Lauderdale Road, Maida Vale, London, England, and 79, Mitcham Lane, Streatham, London, England, respectively, have invented a new and useful Ticket-Delivering Machine, of 10 which the following is a specification.

Our invention relates to an improved construction of ticket delivering machine of the type described in prior Patent No. 1378419 in the name of A. Marsh, and comprises a 15 construction of apparatus for feeding out and cutting off tickets from a roll for actuating a date stamping device and for registering their delivery upon a counter.

The object of this invention is to provide 20 a simplified form of apparatus which will feed out and cut off a ticket accurately at each operation with regularity and reliability, and which will enable the tickets delivered to be stamped with the date of 25 delivery and such delivery registered upon an indicator.

According to this invention, the frame of the machine is provided with a bed over 30 which is supported a hinged frame or cradle and between which the front end of the roll of tickets is located. The forward end of the cradle is pressed upon the top of the ticket so as to hold it firmly upon the table between the feeding operations, which is 35 effected by a pair of rollers, one of which is mutilated and between which the ticket is gripped so as to feed it forward as the rollers rotate. When these rollers engage the ticket the hinged cradle will be lifted 40 so as to permit the forward movement of the ticket. A positive stop is provided and may take the form of a pin or finger adapted to engage a perforation in the ticket roll, preferably located at the junction between 45 two tickets. This finger may be actuated by a cam on the operating shaft of the mutilated feed roller, and is arranged to engage the perforation in the ticket so as to correctly position it after each feeding 50 movement. A cutting knife is mounted upon the forward end of the bed of the machine and is actuated through suitable links from a cam on the main shaft of the mutilated roller. This cutting knife co-acts with 55 a fixed blade on the bed of the machine to

cut off the ticket which has been fed forward by the machine, and the cutting knife may be arranged to engage the lever arm of a registering or counting device so as to register the number of tickets delivered. 60 Means are also provided to actuate a date stamping device, and comprises a lever adapted to be moved against the action of a spring by a suitable cam rotated by the delivery mechanism, this cam being provided with a recess or aperture which permits the spring to return the lever with a rapid movement so that it will strike the date stamping device against the surface of the ticket or an ink ribbon or other marking medium interposed between them. 70

In order that our invention may be readily understood, reference is made to the accompanying drawings, in which:—

Figures 1 and 2 are perspective views 75 from opposite sides showing the embodiment of our invention in a practical form and in which three units are arranged in a single casing.

Figure 3 is a side elevation of the mechanism removed from the casing, and showing a date stamping attachment on one end.

Figure 4 is a view looking on the other side of the mechanism.

Figure 5 is an end view looking on the 85 delivery end of the machine.

Figure 6 is a plan of the same, and

Figure 7 is a longitudinal section showing details of construction.

Referring to Figures 1 and 2, the outer casing 1 is provided with a base 2 by means of which it may be secured upon a counter or other support. Three units 3 are shown in each casing 1, each of which is arranged to deliver tickets from one of the rolls 4 of different priced tickets. These rolls 4 of tickets are supported on brackets 5 on an upright rod 6 having a foot 7 which may be secured to the counter or other support. The rolls of tickets 4 are loosely mounted on a 90 pivot pin 8 which is preferably slightly conical in shape so that as they rotate they will tend to run up the cone toward the bracket 5 so as to automatically retain the roll 4 in position. A roller 9 is supported on a radial arm 10 so as to rest upon the periphery of each roll of tickets 4 and acts to prevent them from rotating too freely. The ticket strip 11 is fed into each unit 3 through a slot 12 and is provided with an operating handle 13 100

110

by which the mechanism of each unit may be actuated to deliver a ticket through a delivery opening 14 on the other side of the casing 1. In Figure 2 a transparent shield 15 is shown over the two upper delivery openings 14 so that the tickets when delivered may fall freely and will not be materially effected by draughts. Apertures 16 are provided on the side of the casing 1 adjacent to each handle 13 through which the dial of the counter on each unit may be viewed.

Referring now to Figures 3, 4, 5, 6 and 7, each ticket delivering machine comprises side frames 20 and 21 which may be cast in brass or other suitable metal, and are provided with lugs 22 by which the machine may be mounted in the casing 1 or other suitable support. The two frames 20 and 21 are secured upon opposite sides of a bed 23 by bolts 24 (see more particularly Fig. 7). The bed 23 is located between the upper edges of the side frames 20 and 21 which are further secured together along their lower edges by bolts 25 and 26 formed with shoulders so as 25 to retain the side frames at the correct distance apart.

Over the bed 23 is provided a hinged frame 27 mounted on a transverse pivot pin 28 whose ends engage in lugs 29 on the side frames 20 and 21. The front end of this hinged frame 27 is resiliently pulled toward the bed 23 by means of coil springs 30 (Figs. 3, 4 and 5) anchored at one end to the bolt 26, and connected at their other end by short 35 links 31 to the ends of a transverse pin 32 passing through the hinged frame 27. The ticket strip 11 rests upon the upper surface of the bed 23 beneath the hinged frame 27 which is provided on its forward edge with a 40 steel or other plate 33 whose lower edge projects slightly so that it will press upon the upper surface of the ticket to grip it firmly, whilst the machine is not in operation. In order to raise the hinged frame 27 against the action of the springs 30, a lever 34 is pivoted at 35 on the side frame 20 and its forward end 36 engages under the projecting end of the pin 32 secured in the frame 27 (see Fig. 6) so that when the end of the lever 34 is depressed, its forward end 36 will rise and lift the front end of the hinged frame 27. This will enable the ticket strip to be readily inserted or removed from the machine when required.

An opening 37 (Fig. 7) is provided in the bed 23 beneath the foremost ticket of the ticket strip 11, which is resting on the bed. A mutilated feed roller 40 (Fig. 7) is mounted on a transverse shaft 41 adapted to rotate 60 in bearings 42 formed on the underside of the bed 23. On one end of this shaft 41 is secured the operating handle 13 by which the machine is actuated. A ratchet wheel 43 is also secured on the shaft 41 and is engaged 65 by a pawl 44 (Fig. 3) so as to prevent rota-

tion of the shaft 43 in the wrong direction. In the hinged frame 27 is provided a loosely pivoted roller 45 located directly above the mutilated roller 40. The diameter of the operative segment of the mutilated roller 40 is 70 such that when it is rotated by turning the handle 13 it will press the ticket hard against the roller 45 which will be gripped between them, and at the same time the front edge of the hinged frame 27 will be raised so that the ticket may be fed forward by the rotation of the mutilated roller 40. The length of the operative surface of this mutilated roller is such that the ticket strip will be fed forward to an extent approximately equal to the length of one ticket at each rotation. When this has been done the mutilated roller will release the ticket and the forward end of the hinged frame 27 will again be pressed upon it so as to hold it on the bed 23. 75

In order to ensure correct location of the ticket between each operation of the machine, and to ensure the cutting of each ticket correctly at the junction between adjacent tickets, a positive stop 50 comprising a slidable bar is located at the forward end of the machine in a substantially vertical position. Its lower end is provided with a guide pin 51 engaging in a transverse aperture in the bolt 26 between the side frames 20 and 21. The upper end of this stop 50 is provided with a finger 52 which projects up into a recess in the plate 33 secured on the front end of the hinged frame 27. Whilst the ticket strip is stationary this finger 52 remains in the higher position as shown in Figs. 5 and 7, and projects through an aperture in the ticket strip so as to positively locate this upon the bed 23 of the machine. Before the ticket can 105 be fed forward this finger 52 is withdrawn from the aperture in the ticket strip by means of the lever 53 engaging in a recess 54 in the stop 50. This lever 53 is mounted on a transverse pin 55 and is rigidly connected to a lever 56 provided at its end with a roller 57 which engages with a cam 58 secured upon the end of the shaft 41 (see Figs. 4, 5, 6 and 7). The lower end of the lever 56 is extended and connected by a 110 spring 59 to the frame 21 so as to retain the roller 57 against the cam 58, and to normally retain the finger 52 in the raised position. When the shaft 41 is rotated so as to bring the feed roller 40 into operation, the cam 58 will press upon the roller 57 turning the lever 56 about its pivot against the action of the spring 59, and at the same time turning the lever 53 so that its end will move the stop 50 downward to withdraw the finger 52 from the aperture in the ticket. The ticket strip will now be free to be moved forward by the action of the feed rollers, and when this has been completed the cam 58 will release the lever 56 permitting the 115 120 125 130

spring 59 to again project the stop 50 upwardly, so as to insert the finger 52 in a new aperture in the ticket strip.

In order to sever each ticket after it is fed forward so that it may fall from the delivery aperture 14, a guillotine knife 60 is mounted transversely across the front end of the machine upon the pivot pin 61 in the lug 62 on the end of the bed 23. A coil spring 63 is provided on this pivot pin 61 so as to urge the knife 60 to the fixed blade 64 mounted upon the end of the bed 23 and with which it co-operates to cut off each ticket after its delivery. The guillotine knife 60 is actuated through a link 65 connected to its free end, and to the end of a lever 66 pivoted on the frame 20 at 67. On this lever 66 is mounted a roller 68 which engages a cam 69 on the shaft 41 (see more particularly Fig. 3). The guillotine knife 60 is normally maintained in the raised position and the roller 68 on the lever 66 is pressed against the cam 69 by means of the coil spring 70 engaging an extension of the guillotine knife 60 at one end, and anchored to one of the lugs 22 of the frame 21 at its other end. In the position shown in Fig. 3, the handle 13 is shown in its lowermost position, and the machine has completed its cycle of operations in delivering a ticket, and is ready to commence a fresh cycle to deliver another ticket. In this position the roller 68 engages in a recess 71 formed in the cam 69, and which serves to locate the handle and the mechanism in the position just described, and to enable the operator to know when it is in this position by the "feel" of the handle. After the ticket strip has been fed forward as previously described by rotating the handle 13 in an anti-clockwise direction as seen in Fig. 3, the cam 69 will come into operation against the roller 68, and will depress the lever 66, thus pulling down the guillotine knife 60 so as to cut off the ticket fed forward. This ticket will then fall from the delivery aperture 14.

When the guillotine knife 60 is nearing its lowermost position, its end will engage a projecting pin 80 on the lever arm 81 of the registering counter 82. This counter will thus be actuated each time a ticket is cut off so as to register its delivery thereon. In this manner the number of tickets delivered by each unit is accurately recorded and may be instantly seen by viewing the dial of its counter through the aperture 16 provided in the casing 1 for this purpose.

When the machine is required for issuing railway and like tickets, it is necessary to stamp the date of delivery upon the ticket when it is issued, and for this purpose a suitable date stamping device of any convenient construction is provided. Such an apparatus is indicated at 90 (Fig. 3), and is supported on the projecting pins 91 pro-

vided on the two side frames 20 and 21 at the rear end of the machine in such a manner that it may be readily detached when required. Such a date stamping apparatus may incorporate suitable printing type 70 adapted to be struck up against the surface of the ticket so as to mark the date of delivery thereon. In order to actuate this date stamping device, a lever 92 is pivoted upon the transverse pin 55 extending between the side frames 20 and 21. This lever is provided with a roller 93 which is held against the edge of a disc 94 by means of a strong coil spring 95 secured to the end of the lever, and to the downwardly projecting lug 96 on the side frame 20. In the edge of this disc 94 is provided a small recess 97 and a larger recess 98. When the operating handle 13 is in its lowermost or neutral position, the roller 93 will rest in the small recess 97 and during its first movement the deeper recess 98 will permit the spring 95 to pull down the end so that the lever 92 will be forced rapidly in an upward direction to cause the projecting pin 99 to strike up the printing type to mark the date upon the ticket. The lever 92 is also shown provided with a pin 100 projecting from its extreme end and adapted to engage in a recess 101 on the frame member 20 so as to limit its upward movement thus allowing the type to strike the ticket under its own momentum, and to immediately fall back so ensuring a clear marking of the ticket. The pawl 44 engaging with the ratchet wheel 43 will prevent the rotation of the handle in the wrong direction, and ensures a complete cycle of operations for each ticket delivered. In order however, to allow for the stamping of the date upon the foremost ticket when the ticket strip is first fed into the machine, the pawl 44 is provided with a roller encased pin 46 which will be engaged by the cam 69 when the handle 13 is in its lowermost or neutral position. This permits the lever to be moved in a reverse direction to a limited extent as the cam 69 will press upon the roller encased pin 46 to throw the pawl 44 out of engagement with the ratchet wheel 43. This will bring the recess 98 in the disc 94 opposite to the roller 93 on the lever 92 thus allowing the spring 95 to actuate this lever and strike up the date stamping device.

The operation of the machine is as follows:—

The lever 34 is depressed so as to raise the hinged frame 27 and permit the end of the ticket strip to be fed along the bed 23 until its forward end engages against the finger 52 on the stop 50. The lever 34 is then released and the frame 27 will press upon and hold the ticket. The handle 13 may now be operated in a reverse direction 130

to a small extent so as to stamp the date on the first ticket of the strip. The machine is now all ready to deliver any number of tickets in succession. The delivery of the tickets is performed by rotating the handle 13 in an anti-clockwise direction. This will first bring the recess 98 in the disc 94 opposite the roller 93 on the lever 92 thus allowing the spring 95 to move the lever 10 sharply in an upward direction so that the pin 99 will actuate the date stamping device to stamp the date upon the second ticket in the machine. At the same time the finger 52 on the stop 50 will be withdrawn from the perforation in the ticket. As the mutilated roller 40 engages the underside of the ticket which is thus gripped between it and the roller 45, the hinged frame 27 will be lifted to release the forward end of the ticket which is then fed forward by the rotation of the mutilated roller 40. When the ticket has been fed forward to the correct distance, the finger 52 will again engage in a perforation in the ticket strip and as the mutilated roller releases contact with the ticket, the hinged frame 27 will drop so as to grip it at its forward end. The pivoted knife 60 is now drawn down so as to cut off the ticket and at the same time actuates the counter arm 81 so as to register the delivery of the ticket upon its dial. This completes the cycle of operations which may be repeated as often as required by merely rotating the handle 13 through a complete circle.

We claim:—

1. In a ticket delivering machine, a rotatable mutilated roller and a freely pivoted roller adapted to grip the ticket strip between them, a main frame and a hinged frame in which these rollers are mounted, means for resiliently pressing the two rollers towards each other, a slideable stop adapted to engage each ticket of the strip in turn so as to positively position it between each movement, a guillotine knife for cutting off each ticket, means for actuating this knife through the rotation of the mutilated roller and means for rotating this roller so as to perform the various operations in succession.

2. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, a slideable stop adapted to engage each ticket in turn so as to positively position it between each movement of the ticket strip, a guillotine knife for cutting off each ticket and

means for actuating this knife through the rotation of the mutilated roller.

3. In a ticket delivering machine, a rotatable mutilated roller, a main frame in which this mutilated roller is mounted on a transverse shaft, a handle for rotating this shaft, a slotted bed to this main frame on which the end of the ticket strip rests, a hinged frame mounted over this bed on the main frame, a freely pivoted roller in this hinged frame, spring means for pressing the hinged frame toward the main frame, a slideable stop adapted to engage each ticket in turn so as to positively position it between each movement of the ticket strip, a guillotine knife for cutting off each ticket, and a cam on the transverse shaft to actuate the guillotine knife after each ticket has been fed forward.

4. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, a slideable stop mounted in the main frame, spring means for urging this stop toward the ticket strip, a finger on the stop adapted to engage automatically in a perforation in each ticket, means for moving the stop so as to withdraw the finger whilst the ticket strip is being fed forward, a guillotine knife for cutting off each ticket and means for actuating this knife through the rotation of the mutilated roller.

5. In a ticket delivering machine, a rotatable mutilated roller, a main frame in which this mutilated roller is mounted on a transverse shaft, a handle for rotating this shaft, a slotted bed to this main frame on which the end of the ticket strip rests, a hinged frame mounted over this bed on the main frame, a freely pivoted roller in this hinged frame, spring means for pressing the hinged frame toward the main frame, a slideable stop mounted in the main frame, spring means for urging this stop toward the ticket strip, a finger on the stop adapted to engage automatically in a perforation in each ticket, means for moving the stop so as to withdraw the finger whilst the ticket strip is being fed forward, a guillotine knife for cutting off each ticket, and a cam on the transverse shaft to actuate the guillotine knife after each ticket has been fed forward.

6. In a ticket delivering machine, a rotatable mutilated roller, a main frame in which this mutilated roller is mounted on a transverse shaft, means for rotating this shaft, a slotted bed to this main frame on which the end of the ticket strip rests, a

hinged frame mounted over this bed on the main frame, a freely pivoted roller in this hinged frame, means for pressing the hinged frame toward the main frame, a 5 slideable stop mounted in the main frame, spring means for urging this stop toward the ticket strip, a finger on the stop adapted to engage automatically in a perforation in each ticket, a cam on the transverse shaft 10 for moving the stop so as to withdraw the finger whilst the ticket strip is being fed forward, a guillotine knife for cutting off each ticket, and means for actuating this knife through the rotation of the mutilated 15 roller.

7. In a ticket delivering machine, a rotatable mutilated roller, a main frame in which this mutilated roller is mounted on a transverse shaft, a handle for rotating this 20 shaft, a slotted bed to this main frame on which the end of the ticket strip rests, a hinged frame mounted over this bed on the main frame, a freely pivoted roller in this hinged frame, spring means for pressing the 25 hinged frame toward the main frame, a slideable stop mounted in the main frame, spring means for urging this stop toward the ticket strip, a finger on the stop adapted to engage automatically in a perforation in each ticket, a cam on the transverse shaft 30 for moving the stop so as to withdraw the finger whilst the ticket strip is being fed forward, a guillotine knife for cutting off each ticket, and a cam on the transverse 35 shaft to actuate the guillotine knife after each ticket has been fed forward.

8. In a ticket delivering machine, a rotatable mutilated roller, a main frame in which this mutilated roller is mounted on a transverse shaft, means for rotating this 40 shaft, a slotted bed to this main frame on which the end of the ticket strip rests, a hinged frame mounted over this bed on the main frame, a freely pivoted roller in this 45 hinged frame, means for pressing the hinged frame toward the main frame, an edge to the hinged frame to press and hold the ticket upon the bed between its feeding movements which will be lifted by the mutilated 50 roller when it grips the ticket between it and the freely pivoted roller to perform the feeding movement, a slideable stop adapted to engage each ticket in turn so as to positively position it between each 55 movement of the ticket strip, a guillotine knife for cutting off each ticket, and means for actuating this knife through the rotation of the mutilated roller.

9. In a ticket delivering machine, a rotatable mutilated roller, a main frame in which this mutilated roller is mounted on a transverse shaft, a handle for rotating this 60 shaft, a slotted bed to this main frame on which the end of the ticket strip rests, a hinged frame mounted over this bed on the 65

main frame, a freely pivoted roller in this hinged frame, spring means for pressing the hinged frame toward the main frame, an edge to the hinged frame to press and hold the ticket upon the bed between its feeding 70 movements which will be lifted by the mutilated roller when it grips the ticket between it and the freely pivoted roller to perform the feeding movement, a slideable stop mounted in the main frame, a spring means 75 for urging this stop toward the ticket strip, a finger on the stop adapted to engage automatically in a perforation in each ticket, means for moving the stop so as to withdraw the finger whilst the ticket strip is 80 being fed forward, a guillotine knife for cutting off each ticket, and a cam on the transverse shaft to actuate the guillotine knife after each ticket has been fed forward.

10. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when it grips the ticket between it and the freely pivoted roller to perform the feeding 90 movement, a slideable stop mounted in the main frame, spring means for urging this stop toward the ticket strip, a finger on the stop adapted to engage automatically in a perforation in each ticket, a cam on the transverse shaft for moving the stop so as to withdraw the finger whilst the ticket strip is being fed forward, a guillotine knife for cutting off each ticket, and means for actuating this knife through the rotation of the mutilated 95 roller.

11. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when it grips the ticket between it and the freely pivoted roller to perform the feeding movement, a pivoted lever for manually lifting the hinged frame when inserting or removing the ticket strip, a slideable stop adapted to engage each ticket in turn so as to positively position it between each move- 115 120 125 130

ment of the ticket strip, a guillotine knife for cutting off each ticket, and means for actuating this knife through the rotation of the mutilated roller.

- 5 12. In a ticket delivering machine, a rotatable mutilated roller, a main frame in which this mutilated roller is mounted on a transverse shaft, a handle for rotating this shaft, a slotted bed to this main frame on which the end of the ticket strip rests, a hinged frame mounted over this bed on the main frame, a freely pivoted roller in this hinged frame, a spring means for pressing the hinged frame toward the main frame, an 10 edge to the hinged frame to press and hold the ticket upon the bed between its feeding movements which will be lifted by the mutilated roller when it grips the ticket between it and the freely pivoted roller to perform 15 the feeding movement, a pivoted lever for manually lifting the hinged frame when inserting or removing the ticket strip, a slide- 20 able stop mounted in the main frame, spring means for urging this stop toward the ticket strip, a finger on the stop adapted to engage automatically in a perforation in each ticket, means for moving the stop so as to withdraw the finger whilst the ticket strip is being fed forward, a guillotine knife 25 for cutting off each ticket, and a cam on the transverse shaft to actuate the guillotine knife after each ticket has been fed forward.

- 30 13. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding 35 movements which will be lifted by the mutilated roller when it grips the ticket between it and the freely pivoted roller to perform the feeding movement, a pivoted lever for manually lifting the hinged frame when inserting or removing the ticket strip, a slide- 40 able stop mounted in the main frame, spring means for urging this stop toward the ticket strip, a finger on the stop adapted to engage automatically in a perforation in each ticket, 45 means for moving the stop so as to withdraw the finger whilst the ticket strip is being fed forward, a guillotine knife for cutting off each ticket and means for actuating this 50 knife through the rotation of the mutilated roller.

- 55 14. In a ticket delivering machine, a rotatable mutilated roller, a main frame in which this mutilated roller is mounted on a transverse shaft, means for rotating this

shaft, a slotted bed to this main frame on which the end of the ticket strip rests, a hinged frame mounted over this bed on the main frame, a freely pivoted roller in this hinged frame, means for pressing the hinged frame toward the main frame, a slide- 60 able stop adapted to engage each ticket in turn so as to positively position it between each movement of the ticket strip, a knife pivotally mounted on the front end of the machine and cooperating with a fixed blade thereon, and a cam in rotational engagement with the mutilated roller, a lever and link actuated by the cam to draw down the knife and cut off the ticket at the correct moment 65 after it has been fed forward.

70 15. In a ticket delivering machine, a rotatable mutilated roller, a main frame in which this mutilated roller is mounted on a transverse shaft, a handle for rotating this shaft, a slotted bed to this main frame on which the end of the ticket strip rests, a hinged frame mounted over this bed on the main frame, a freely pivoted roller in this hinged frame, spring means for pressing the hinged frame toward the main frame, a slide- 75 able stop mounted in the main frame, spring means for urging this stop toward the ticket strip, a finger on the stop adapted to engage automatically in a perforation in each ticket, 80 means for moving the stop so as to withdraw the finger whilst the ticket strip is being fed forward, a knife pivotally mounted on the front end of the machine and co-operating with a fixed blade thereon, a cam in 85 rotational engagement with the mutilated roller, and a lever and link actuated by the cam to draw down the knife and cut off the ticket at the correct moment 90 after it has been fed forward.

95 16. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, a slide- 100 able stop mounted in the main frame, spring means for urging this stop toward the ticket strip, a finger on the stop adapted to engage automatically in a perforation in each ticket, 105 a cam on the transverse shaft for moving the stop so as to withdraw the finger whilst the ticket strip is being fed forward, a knife pivotally mounted on the front end of the machine and co-operating with a fixed blade thereon, a cam in rotational engagement 110 with the mutilated roller, and a lever and link actuated by the cam to draw down the knife and cut off the ticket at the correct moment 115 after it has been fed forward.

120 17. In a ticket delivering machine, a rotat-

able mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when it grips the ticket between it and the freely pivoted roller to perform the feeding movement, a slidable stop adapted to engage each ticket in turn so as to positively position it between each movement of the ticket strip, a knife pivotally mounted on the front end of the machine and co-operating with a fixed blade thereon, a cam in rotational engagement with the mutilated roller, and a lever and link actuated by the cam to draw down the knife and cut off the ticket at the correct moment after it has been fed forward.

18. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when it grips the ticket between it and the freely pivoted roller to perform the feeding movement, a pivoted lever for manually lifting the hinged frame when inserting or removing the ticket strip, a slidable stop mounted in the main frame, spring means for urging this stop toward the ticket strip, a finger on the stop adapted to engage automatically in a perforation in each ticket, a cam on the transverse shaft to actuate the guillotine knife after each ticket has been fed forward, a date stamping device mechanism for actuating said date stamping device comprising a lever, a disc on the transverse shaft, spring means for pressing one end of the lever against this disc, a recess in the disc to allow the spring means to actuate the lever and strike the date stamping means against the ticket.

19. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged

frame, means for pressing the hinged frame toward the main frame, a slidable stop adapted to engage each ticket in turn so as to positively position it between each movement of the ticket strip, a guillotine knife for cutting off each ticket, means for actuating this knife through the rotation of the mutilated roller, a date stamping device mechanism for actuating said date stamping device comprising a lever, a disc on the transverse shaft, spring means for pressing one end of the lever against this disc, a recess in the disc to allow the spring means to actuate the lever and strike the date stamping means against the ticket.

20. In a ticket delivering machine, a rotatable mutilated roller, a main frame in which this mutilated roller is mounted on a transverse shaft, a handle for rotating this shaft, a slotted bed to this main frame on which the end of the ticket strip rests, a hinged frame mounted over this bed on the main frame, a freely pivoted roller in this hinged frame, spring means for pressing the hinged frame toward the main frame, a slidable stop mounted in the main frame, spring means for urging this stop toward the ticket strip, a finger on the stop adapted to engage automatically in a perforation in each ticket, means for moving the stop so as to withdraw the finger whilst the ticket strip is being fed forward, a guillotine knife for cutting off each ticket, a cam on the transverse shaft to actuate the guillotine knife after each ticket has been fed forward, a date stamping device mechanism for actuating said date stamping device comprising a lever, a disc on the transverse shaft, spring means for pressing one end of the lever against this disc, a recess in the disc to allow the spring means to actuate the lever and strike the date stamping means against the ticket.

21. In a ticket delivering machine, a rotatable mutilated roller, a main frame in which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when it grips the ticket between it and the freely pivoted roller to perform the feeding movement, a slidable stop mounted in the main frame, spring means for urging this stop toward the ticket strip, a finger on the stop adapted to engage automatically in a perforation in each ticket, a cam on the transverse shaft for moving the stop so as to withdraw the

- finger whilst the ticket strip is being fed forward, a guillotine knife for cutting off each ticket, means for actuating this knife through the rotation of the mutilated roller,
- 5 a date stamping device mechanism for actuating said date stamping device comprising a lever, a disc on the transverse shaft, spring means for pressing one end of the lever against this disc, a recess in the disc to allow
- 10 the spring means to actuate the lever and strike the date stamping means against the ticket.
22. In a ticket delivering machine, a rotatable mutilated roller, a main frame in
- 15 which this mutilated roller is mounted on a transverse shaft, means for rotating this shaft, a slotted bed to this main frame on which the end of the ticket strip rests, a hinged frame mounted over this bed on the
- 20 main frame, a freely pivoted roller in this hinged frame, means for pressing the hinged frame toward the main frame, a slidable stop adapted to engage each ticket in turn so as to positively position it be-
- 25 tween each movement of the ticket strip, a knife pivotally mounted on the front end of the machine, and co-operating with a fixed blade thereon, a cam in rotational engagement with the mutilated roller, a lever
- 30 and link actuated by the cam to draw down the knife and cut off the ticket at the correct moment after it has been fed forward, a date stamping device mechanism for actuating said date stamping device comprising
- 35 a lever, a disc on the transverse shaft, spring means for pressing one end of the lever against this disc, a recess in the disc to allow the spring means to actuate the lever and strike the date stamping means against
- 40 the ticket.
23. In a ticket delivering machine, a rotatable mutilated roller, a main frame in
- 45 which this mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, means for pressing the
- 50 hinged frame toward the main frame, an edge to the hinged frame to the press and hold the ticket upon the bed between its feeding movements which will be lifted by the mutilated roller when it grips the ticket
- 55 between it and the freely pivoted roller to perform the feeding movement, a pivoted lever for manually lifting the hinged frame when inserting or removing the ticket strip, a slidable stop mounted in the main frame, spring means for urging this stop toward
- 60 the ticket strip, a finger on the stop adapted to engage automatically in a perforation in each ticket, a cam on the transverse shaft for moving the stop so as to withdraw the finger whilst the ticket strip is being fed
- forward, a knife pivotally mounted on the front end of the machine and co-operating with a fixed blade thereon, a cam in rotational engagement with the mutilated roller, a lever and link actuated by the cam to 70 draw down the knife and cut off the ticket at the correct moment after it has been fed forward, a registering counter upon the machine having a movable arm adapted to be engaged by the pivoted knife each 75 time this is operated so as to move the counter arm and register the delivery of each ticket, a date stamping device mechanism for actuating said date stamping device, comprising a lever, a disc on the trans- 80
- 85 verse shaft, spring means for pressing one end of the lever against this disc, a recess in the disc to allow the spring means to actuate the lever and strike the date stamping means against the ticket.
24. In a ticket delivering machine, a rotatable mutilated roller, a main frame in which this mutilated roller is mounted on a transverse shaft, means for rotating this shaft, a slotted bed to this main frame on 90 which the end of the ticket strip rests, a hinged frame mounted over this bed on the main frame, a freely pivoted roller in this hinged frame, means for pressing the hinged frame toward the main frame, a slidable 95 stop adapted to engage each ticket in turn, so as to positively position it between each movement of the ticket strip, a guillotine knife for cutting off each ticket, means for actuating this knife through the rotation 100 of the mutilated roller, a ratchet wheel in rotational engagement with the mutilated roller, a pawl adapted to engage therewith to normally prevent movement in a reverse direction, and means to hold the pawl out of action during a small portion of the rotational movement of the mutilated roller.
- 105
25. In a ticket delivering machine, a rotatable mutilated roller, a main frame in which this mutilated roller is mounted on a trans- 110
- 115 verse shaft, means for rotating this shaft, a slotted bed to this main frame on which the end of the ticket strip rests, a hinged frame mounted over this bed on the main frame, a freely pivoted roller in this hinged frame, means for pressing the hinged frame toward the main frame, an edge to the hinged frame to press and hold the ticket upon the bed between its feeding movements which will be lifted by the mutilated roller when 120 it grips the ticket between it and the freely pivoted roller to perform the feeding movement, a slidable stop adapted to engage each ticket in turn so as to positively position it between each movement of the ticket strip, a guillotine knife for cutting off each ticket and means for actuating this knife through the rotation of the mutilated roller, a ratchet wheel in rotational engagement with the mutilated roller, a pawl adapted to engage 125
- 130

therewith to normally prevent movement in a reverse direction, and means to hold the pawl out of action during a small portion of the rotational movement of the mutilated 5 roller.

26. In a ticket delivering machine, a rotatable mutilated roller, a main frame in which this mutilated roller is mounted on a transverse shaft, means for rotating this 10 shaft, a slotted bed to this main frame on which the end of the ticket strip rests, a hinged frame mounted over this bed on the main frame, a freely pivoted roller in this hinged frame, means for pressing the hinged 15 frame toward the main frame, a slideable stop adapted to engage each ticket in turn so as to positively position it between each movement of the ticket strip, a knife pivotally mounted on the front end of the machine and co-operating with a fixed blade thereon, a cam in rotational engagement with the mutilated roller, a lever and link actuated by the cam to draw down the knife and cut off the ticket 20 at the correct moment after it has been fed forward, a date stamping device mechanism for actuating said date stamping device comprising a lever, a disc on the transverse shaft, spring means for pressing one end of the lever against this disc, a recess in the disc to allow the spring means to actuate the lever and date stamping means against the ticket, a ratchet wheel in rotational engagement with the mutilated roller, a pawl 25 adapted to engage therewith to normally prevent movement in a reverse direction, and means to hold the pawl out of action during a small portion of the rotational movement of the mutilated roller.

27. In a ticket delivering machine, a rotatable mutilated roller, a main frame in which

the mutilated roller is mounted on a transverse shaft, means for rotating this shaft, a slotted bed to this main frame on which the end of the ticket strip rests, a hinged frame mounted over this bed on the main frame, a freely pivoted roller in this hinged frame, 35 means for pressing the hinged frame toward the main frame, a slideable stop adapted to engage each ticket in turn, so as to positively position it between each movement of the ticket strip, a knife pivotally mounted 40 on the front end of the machine and co-operating with a fixed blade thereon, a cam in rotational engagement with the mutilated roller, a lever and link actuated by the cam to draw down the knife and cut off the ticket 45 at the correct moment after it has been fed forward, a date stamping device mechanism for actuating said date stamping device comprising a lever, a disc on the transverse shaft, spring means for pressing one end of the lever against this disc, a recess in the disc to allow the spring means to actuate the lever and date stamping means against the ticket, a ratchet wheel in rotational engagement with the mutilated roller, a pawl 50 adapted to engage therewith to normally prevent movement in a reverse direction, and means to hold the pawl out of action during a small portion of the rotational movement of the mutilated roller.

ALBERT MARSH.
HERBERT PHILIP ALAIS.
